United States Patent Office.

JOSHUA F. HAMMOND, OF PROVIDENCE, RHODE ISLAND, ASSIGNOR TO
HENRY STAPLES AND COMPANY.

Letters Patent No. 67,534, dated August 6, 1867.

IMPROVED KNIFE-CLEANER.

The Schedule referred to in these Letters Patent and making part of the same.

TO WHOM IT MAY CONCERN:

Be it known that I, JOSHUA F. HAMMOND, of Providence, Rhode Island, have invented new and useful improvements in Knife-Polishers; and I do hereby declare the following to be a full and exact description of the same, reference being had to the drawings that accompany and form a part of these specifications, in which—

Figure 1 is a sectional view.

Figure 2, view of the article in use.

Figure 3, view of position for applying the polishing-powder.

Letter A represents a metallic socket, with shank for handle; letter B, a little cup, with cover, containing the polishing-powder; letter C, a cork pressed firmly into the socket A; letter D, the handle.

The object of my invention is to provide a more convenient polisher than has been heretofore offered, both as to the manner of keeping and applying the powder, and as to the manner of holding the cork, or whatever is used to produce the rubbing or friction.

The socket A may be made of common castings, and should be of sufficient depth to hold the cork well. The cups are readily made of sheet tin, and may be in diameter larger than the flange of the socket on which they stand, if desired. A few small holes are made in the cap of the cup, as represented in fig. 3. These holes should be very small, and on that part of the disk shown in fig. 3, as thus it is more convenient in use.

A cork is often taken in the fingers to rub upon a knife, which is not easy. In my device the hand can grasp firmly the handle, readily give the proper pressure of the cork upon the knife, and when more powder is required, a turn of the wrist bringing the position shown in fig. 3.

The cup B may be soldered or riveted to the socket, or attached in any other convenient manner. The shank of the socket may be straight, as represented in fig. 1, or curved, as shown in fig. 2.

What I claim, and desire to secure by Letters Patent, is—

The socket A, the cup B, with its cap provided with the small openings, and the cork C, or its equivalent, all arranged substantially as described and for the purposes set forth.

In testimony whereof I have signed my name to this specification in the presence of two subscribing witnesses.

JOSHUA F. HAMMOND.
